Morrison and Tibbits, Assignees of Abram Naney, Troy, New York
Letters Patent. No 248. Dated November 6th 1849.
The Schedule referred to in these Letters Patent and making
part of the same.

To all whom it may concern: Be it Known

that I, Abram Naney of the City of Troy, in the State
of New York have produced a new ornamental design for
a Diving Flue Grate. And I do hereby declare that the
annexed and accompanying drawings are a full and accurate de-
lineation of such plates as I desire to secure by Patent. The half of
figures A + B that are shown only in outline being symmetrical with
those fully represented,

What I claim as my Invention and desire to
secure by Letters Patent is the design for a Diving Flue Grate as shown
and described in the Specification and Drawings. Figures A. B. C + D.
